STAIRS

John Patrick MacDonald, Ottawa, Ontario,
CanadaApplication March 29, 1935, Serial No. 13,612
In Canada March 16, 1935

8 Claims. (Cl. 189—43)

My invention relates to stairs.

It is well known that the cost of stairs for houses constitutes an appreciable part of the cost of a house complete. The building of stairs also calls for special skill and experience which are usually possessed only by stair builders and not by the majority of carpenters.

The relatively high cost of building stairs is a result of many factors, other than the relatively high wages which must be paid to skilled men. One of these factors is that stairs, that is, risers and treads cannot be manufactured in large quantities at the factory, to standard sizes or dimensions, for the reason that even houses built according to definite specifications will be found in practice to vary appreciably in so far as the distance between two floors is concerned. Where similar stairs are manufactured at the factory, for houses built according to the same specification, it is found that the height of the risers intended for a certain stair has to be varied.

As will be presently seen, the riser and tread made according to my invention, and which are made of sheet metal or thin metal, are such that they can be easily assembled and adjusted relatively to one another. They can be manufactured in quantities at the factory, brought to the house under erection, and installed at their required respective positions without alteration thereto.

Their relative adjustability will thus take care of appreciable variations in the rise or distance between floors, and the run of horizontal span.

My invention is not concerned with houses of the superior type, nor with office buildings or the like wherein the stair treads are covered with cement or similar substances, but with houses of moderate prices.

The objects of my invention, therefore, are to design treads and risers for stairs which will be relatively adjustable in respect of both vertical and horizontal planes, thereby appreciably reducing the cost of installing stairs.

As constructed and assembled, the treads and risers will permit of an appreciable range of adjustment, and will present a neat and finished appearance without having to be covered as with cement, carpet or otherwise.

In the drawing, wherein like numerals of ref-

erence indicate corresponding parts in various figures.

Figure 1 is a fragmentary, cross-sectional view of a stair made in accordance with my invention;

Figure 2 is a fragmentary, front elevation of the riser;

Figure 3 is a plan view of the brace or tread support;

Figure 4 is a fragmentary, plan view of the tread.

Referring now by numerals to the drawing, A indicates the stairs, B the wall stringer (two stringers being used as usual, one on each side of the stairs) C the lower floor from which the stair rises, and C' the upper floor.

1 is the tread, and 2 the riser so designed as to constitute a unit, in the sense that both members that is riser and tread are made to be easily assembled together and relatively adjustable whereby to adjust the same in respect of both vertical and horizontal planes to accordingly vary the effective height of the riser and the effective width of the tread. It will be evident that by effective height of the riser is meant the lift or distance between two consecutive treads, or between floor and tread as the case may be, and by effective width of tread is meant the horizontal distance between the outer edge of the tread and the next riser as measured in the longitudinal axis of the stair.

The riser is formed with a right angularly arranged turned-out flange 3 adapted to rest upon and engage the upper face of the tread lying below, or the floor as the case may be. The lowermost riser may be secured to the floor as with screws 4, while the other risers may be secured to their respective treads as with stove bolts 4A or the like. The vertical face of each riser may be formed with a right-angularly arranged turned out lug 7 adapted to engage the stringer to which it may be secured as with screws 8.

The tread may be formed as shown having a turned-down flange 21 adapted to engage the outer vertical face of the adjacent riser. The flange may be secured to the riser as with stove bolts 14 and the like. The tread may be formed with end, right-angularly arranged turned-up lugs 5 adapted to engage the stringers and se-

cured thereto as with screws 6. These lugs may also be turned down, if desired, although for many reasons, they should preferably be turned up as shown. These lugs may be extended to about the forward edge or nosing 12 of the tread, if desired. Preferably, end lugs 9 may be formed at each end of the tread, forwardly of the turned down flange 21, and under the nosing 12, these lugs being secured to the stringer, say with screws 10.

If preferred, supports or braces 17 may be used between adjacent riser and tread, as best shown in Figure 1. The support may be formed as shown in Figure 3, having a web 29 and horizontal and vertical flanges 22 and 23 respectively. The flange 23 is perforated as at 24 to receive the bolt 14, while the flange 22 is slotted as at 25 to adjustably receive the bolt 4A.

If preferred an angle 15 may be used under the tread, whether a support such as 17 be used or not. The angle may be secured in place by the bolts 4A. Such an angle should preferably extend substantially over the entire length of the tread that is from about stringer to stringer. Preferably also, the tread is provided with a turned-down flange 16 at the inner end thereof. Such members as the angle 15, the supports 17, lugs 9, and flange 16 will obviously result in a more rigid stair as a whole.

In order to permit of the adjustment of the tread in a vertical plane, relatively to the riser, the riser may be slotted as at 18. The tread may thus be shifted up or down on the riser, to the desired position, after which the nuts on the bolts 14 are tightened. If preferred, lock nuts or spring washers may be used, or else the end of the bolt shank burred to permanently secure the nut in place.

Preferably, the flange 21 of the tread and the vertical face of the riser are serrated or corrugated adjacent the slots 18, as shown at 19, in Figure 2, that is, where both tread and riser are forced together by the bolts 14, the purpose being to increase the friction between both these members after they have been finally assembled. Such serrations will, in fact, provide a positive lock between both members as long as the nuts on the bolts do not appreciably turn.

In order to permit of the adjustment of the riser in a horizontal plane relatively to the tread, the horizontal face of the tread may be slotted as at 20 to slidably receive the bolts 4A. Instead of providing slots, such as 18 and 20, the metal may be stamped to form so-called knock-outs, or discs, any one of which can be knocked out or removed once the right position of the tread or riser has been determined.

While the riser is secured to the tread lying above as with bolts 14, it is evident that the uppermost riser would be secured to the floor as with screws 11 or the like.

The invention contemplates the use of wood stringers, which will permit of the use of screws such as 6, 8 and 10, and provide for the easy and inexpensive fastening of the lugs 5, 7 and 9 in the required position on the stringers. Metal-covered stringers could also be used without adding much to the cost of installation. Where all metal stringers would be used, holes would have to be drilled and tapped after the exact positions of the treads and risers had been determined. In such a case, machine bolts would preferably be used and the cost of installation would be somewhat increased.

It will be seen that once the risers and treads

are assembled, the stairs will present a neat and finished appearance. By providing a flange 3 from the riser adapted to engage the upper face of the tread, and by providing knock-outs instead of slots 20 and 18, a large range of adjustment is possible of the riser on the tread and of the tread on the riser. 5

Operation

The most expeditious and inexpensive method 10 of installing my stair is as follows:

After the exact rise and run have been determined and the stringers accordingly cut to the required size, the respective positions of the risers and treads are determined and marked off on 15 the stringers, all according to usual practice. The stringers are laid upon the floor or work benches and one proceeds to assemble the risers and treads to the stringers. Preferably, the lowermost riser is first secured to the stringers, although the uppermost tread may first be secured in place. The riser is thus secured by means of the screws 8. The first tread is next applied, the screws 6 securing the lugs 5 to the stringers and the screws 10 through the lugs 9 (where such are used) 25 securing these lugs to the stringers; the bolts 14 fasten the riser to the tread. The next or second riser is now applied; and so on.

What I claim is:—

1. In stairs, a unit comprising a metal riser 30 and a metal tread adjustably securable together, said riser terminating at the bottom in a right-angularly arranged flange engaging the upper face of said tread to permit of their relative adjustment in a horizontal plane, and means for 35 adjustably securing said flange to said tread.

2. In stairs, a unit comprising a metal riser and a metal tread adjustably securable together, said tread terminating at the forward edge in a downwardly-extending flange engaging one face 40 of said riser to permit of their relative adjustment in a vertical plane, and means for adjustably securing said flange to said riser.

3. In stairs, a unit comprising a metal riser and a metal tread adjustably securable together, 45 said tread having a turned-down and turned-in forward portion forming a nosing and a downwardly-extending flange from the nosing engaging the forward face of said riser to permit of the relative adjustment of said riser and tread 50 in a vertical plane, and means for adjustably securing said flange to said riser.

4. In combination with a stair stringer, a unit comprising a metal riser and a metal tread, said riser terminating at the bottom in a right-angul- 55 larly arranged flange engaging the upper face of said tread to permit of their relative adjustment in a horizontal plane, means adjustably securing said flange to said tread, said riser having a lug adapted to engage the stringer, and means 60 securing said lug to the stringer.

5. In combination with a stair stringer, a unit comprising a metal riser and a metal tread, said tread terminating at the forward edge in a downwardly-extending flange engaging one face of 65 said riser to permit of their relative adjustment in a vertical plane, means adjustably securing said flange to said riser, said tread having a lug engaging the stringer, and means securing said lug to the stringer. 70

6. In combination with a stair stringer, a unit comprising a metal riser and a metal tread, said tread having a turned-down and turned-in forward portion forming a nosing and a downwardly-extending flange from the nosing engaging the 75

forward face of said riser to permit of their relative adjustment in a vertical plane, means adjustably securing said flange to said riser, said tread having an end lug adjacent the nosing, and 5 means securing said lug to the stair stringer.

7. In stairs, a unit comprising a metal riser and a metal tread adjustably securable together, said riser terminating at the bottom in a right- 10 angularly arranged flange engaging the upper face of said tread to permit of their relative adjustment in a horizontal plane, and means for adjustably securing said flange to said tread, said tread terminating at the rear edge in a right-

angularly turned flange forming a stiffening member for said tread.

8. In stairs, a unit comprising a metal riser and a metal tread adjustably securable together, said riser terminating at the bottom in a right- 5 angularly arranged flange engaging the upper face of said tread to permit of their relative adjustment in a horizontal plane, means for adjustably securing said flange to said tread, and a support between said riser and tread and positioned under the latter. 10

JOHN PATRICK MACDONALD.
